CLAIM

The ornamental design for the nose piece for use with eyeglasses, as shown and described.

DESCRIPTION

FIG. 1 is a rear, top and right side perspective view of the nose piece for use with eyeglasses showing my new design, the eyeglasses being shown in broken lines for illustrative purposes only;

FIG. 2 is an enlarged top plan view thereof;

FIG. 3 is an enlarged front elevational view thereof;

FIG. 4 is an enlarged right side elevational view thereof, the left side being a mirror image;

FIG. 5 is an enlarged bottom plan view thereof; and,

FIG. 6 is an enlarged rear elevational view thereof.
